US0D1055856S

(12) **United States Design Patent** (10) Patent No.: **US D1,055,856 S**
(45) Date of Patent: ** Dec. 31, 2024

(54) **VACUUM GENERATOR**

(71) Applicant: **Shenzhen Veestb Technology Co., Ltd.**, Shenzhen (CN)

(72) Inventor: **Zhengxiong Peng**, Shenzhen (CN)

(73) Assignee: **Shenzhen Veestb Technology Co., Ltd.**, Shenzhen (CN)

(**) Term: **15 Years**

(21) Appl. No.: **29/954,547**

(22) Filed: **Jul. 26, 2024**

(51) LOC (14) Cl. **13-01**

(52) U.S. Cl.

USPC **D13/112**

(58) **Field of Classification Search**

(57) **CLAIM**

The ornamental design for a vacuum generator, as shown and described.

DESCRIPTION

FIG. 1 is a front, left and top perspective view of a vacuum generator showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the vacuum generator that form no part of the claimed design.

1 Claim, 8 Drawing Sheets

FIG. 1
